UNITED STATES PATENT OFFICE.

CARLISLE MASON, OF WYNDMOOR, PENNSYLVANIA, ASSIGNOR TO NELSON VALVE COMPANY, A CORPORATION OF PENNSYLVANIA.

DESIGN FOR A WHEEL.

42,855.

Specification for Design.

Patented Aug. 6, 1912.

Application filed May 1, 1912. Serial No. 694,587. Term of patent 14 years.

To all whom it may concern:

Be it known that I, CARLISLE MASON, a citizen of the United States, and a resident of Wyndmoor, county of Montgomery, and State of Pennsylvania, have invented a new, original, and ornamental Design for Wheels, of which the following is a specification, reference being had to the accompanying drawing.

In the accompanying drawing, Figure 1 is a front face view of a wheel showing my

new design; Fig. 2 is an edge view of said wheel; and Fig. 3 is a back face view of the wheel.

I claim:

The ornamental design for a wheel, substantially as shown.

CARLISLE MASON.
